FIREARM

Crawford C. Loomis, Ilion, N. Y., assignor to
Remington Arms Company, Inc., a corporation
of Delaware

Application October 31, 1931, Serial No. 572,263

11 Claims. (Cl. 42—17)

This invention relates to firearms, and contemplates an improvement in "take-down mechanism" for firearms of the repeating type.

Repeating firearms, particularly shot guns, are usually provided with a tubular magazine arranged below and substantially parallel with the barrel, these magazines being adapted to contain a column of cartridges which are delivered to the firing chamber one at a time by the use of suitable mechanism arranged in the receiver. When the gun is "taken down", that is when the barrel or barrel assembly is removed from the receiver and stock assembly, for greater convenience in carrying or shipment, the magazine tube may be removed from the receiver with the barrel, or it may remain fixed to the receiver, the barrel being detached therefrom. In the latter case a detachable connection must be provided between the forward end of the magazine tube and the barrel. This connection ordinarily takes the form of a lug rigidly secured to and depending from the barrel at a position adjacent to the end of the magazine tube, the magazine tube and barrel lug being provided with cooperating fastening means which may be so arranged that the magazine is held in compression between the barrel lug and the receiver, and the section of the barrel between the receiver and the end of the magazine tube is held in tension. It is very desirable that the securing device be such as to prevent any relative movement between the forward end of the magazine and the barrel. Any looseness at this point is annoying and may become dangerous inasmuch as excessive looseness would permit a rotation of the barrel relative to the receiver. The usual fore-end securing device or "take-down joint" comprises a threaded element by the manipulation of which a magazine and barrel lug joining member is advanced to form a secure connection. However, when the firearm is thus assembled, all the parts are at normal temperature, and if thereafter it is used rapidly and continuously, as in trap shooting, the barrel becomes heated and its expansion loosens the take-down joint. The shooter may correct this looseness by further advancing the barrel lug and magazine joining member with the barrel thus expanded, but upon the subsequent cooling and contraction of the barrel the magazine and the take-down mechanism are so tightly compressed that manipulation of the latter is impossible.

It is an object of the present invention to provide a take-down mechanism which is self-compensating for temperature changes due to rapid

shooting or other causes, and one which at all times maintains a satisfactorily rigid connection between barrel and magazine while being incapable of at any time becoming set or subjecting its own mechanism or the magazine tube to excessive strains.

In the drawing:

Fig. 1 is a fragmentary side elevation of as much of a firearm as is necessary to show the application of my invention thereto. 10

Fig. 2 is a fragmentary, central, sectional elevation of the fore-end part of a firearm embodying the invention.

Fig. 3 is a transverse section substantially on the line 3—3 of Fig. 2. 15

Fig. 4 is a transverse section substantially on the line 4—4 of Fig. 2.

For the purpose of illustration, the invention has been shown as applied to a firearm of the type illustrated in Patent No. 1,834,410, issued December 1, 1931.

The firearm comprises a barrel 21 and a magazine tube 22, said tube being rigidly secured in the receiver 20, while the barrel is attached to the receiver 20 by means of an interrupted 25 thread and adapted for removal therefrom by a 90° rotation when released from the forward end of the magazine tube. Rigidly secured to the underside of the barrel 21 is a barrel lug 23, the lower end of which is of reduced longitudinal 30 dimensions, as clearly shown in Fig. 2, and is apertured to receive a stud 24 which may be held therein by a transverse pin 25 engaging an annular groove in the stud 24. The stud 24 comprises a conical head 241, bearing against the 35 rearward face of the barrel lug 23, and may terminate in a cylindrical projection 242. The forward end of the magazine tube 22 is closed by parts including a magazine tube plug 26, said plug comprising a transversely extending elongated aperture adapted to receive an assembly pin 27, the plug being movable on said pin by reason of the elongation of the pin-receiving aperture. Said plug 26 is exteriorly threaded to receive a knurled and interiorly threaded nut 45 28 which is mounted for rotation, but not translation, with respect to the end of the magazine tube. Said nut is held from longitudinal or translational movement by the engagement with grooves therein of key members 29 which are 50 retained in slots formed in a filler ring 30 which fits within the end of the magazine tube surrounding the plug 26 and is rigidly held in place by assembly pin 27.

The parts thus far described are substantially 55

similar to those disclosed in my prior application before mentioned. In said application, however, the end of the magazine plug comprises a conical recess which directly engages the conical head of the barrel lug stud. It will be readily seen that if the barrel is expanded by the heating incident to continuous shooting and the magazine plug is thereafter advanced into close engagement with the barrel lug stud, subsequent cooling of the barrel will place the take-down mechanism under such excessive compression that manipulation of the plug retracting nut will be impossible. In the present construction, this difficulty is obviated as follows:

The head 241 of the barrel lug stud is engaged by the recessed end of a floating take-down piece 31 which is received in a longitudinal bore extending throughout the magazine plug 26. The forward end of said bore is of reduced diameter, and the diameter of the take-down piece is accordingly reduced. The enlarged diameter section of the take-down piece 31 comprises an elongated transversely extending aperture to receive the assembly pin 27, and said piece 31 may terminate a short distance to the rear of the assembly pin 27, or it may be provided with a projecting spring pilot 32, as shown in Fig. 2. The rearward end of the magazine plug bore, which may be somewhat enlarged, is arranged to receive and retain a suitable spring abutment such as a threaded screw 33 which may be provided with a spring pilot 34. A stiff spring 35 is compressed between the abutment piece or screw 33 and the rearward end of the take-down piece 31, whereby the take-down piece is at all times urged forwardly with sufficient force to properly engage the barrel lug stud 24 and hold the magazine tube and barrel in rigid assembly.

Means are provided for co-operating with the novel take-down mechanism heretofore described for insuring the proper positioning of the barrel with respect to both the receiver and the magazine including the take-down devices. As heretofore stated, the barrel is provided with an interrupted thread which engages a corresponding interrupted thread in the receiver. It is important that all of the threads be engaged both to secure a mechanical connection of the proper strength and to place the barrel lug and parts carried thereby in the correct position for engagement with the take-down piece. For this purpose, a small lug 36 is secured to the barrel in a location such that when the barrel is inserted to the correct position in the receiver said lug stands immediately behind the magazine yoke piece 361 in which the barrel lies. When the barrel is turned to the position in which the interrupted threads are disengaged, the lug 36 lies above the end of yoke 361, so that the barrel may be drawn forward. However, in assembly the barrel must be fully inserted in the receiver to bring the lug 36 back of yoke 361 and permit rotation of the barrel. Such rotation is stopped when the barrel reaches its correct angular position with the interrupted threads fully engaged and stud 24 on the barrel lug is in alignment with the take-down piece 31 by the engagement of a shoulder 38 on the barrel lug 23 with the margin of a cut-out 37 in the magazine plug 26. It is thus impossible to assemble the gun without having the barrel fully entered in the receiver, and the rotation of the barrel to its assembled position is facilitated by the provision of a positive stop for the barrel when in this position.

In order to take down the gun, the take-down piece is retracted by rotation of the nut 28, which rotation retracts the magazine plug 26, the internal shoulders 261 thereof engaging the corresponding shoulders of the take-down piece 31 and retracting said piece against the compression of spring 35.

In assembly, the barrel is inserted in the receiver until the lug 36 clears the yoke 361 and is then rotated, engaging the interrupted threads 10 on barrel and receiver, until the shoulder 38 engages the margin of cut-out 37. The take-down piece is then permitted to advance by reversely rotating the nut 28 and thereby advancing the magazine plug 26, but the take-down 15 piece is not directly connected with the magazine plug and only advances under the force of spring 35. As the barrel becomes heated and expands under continuous firing, the spring 35 automatically advances the take-down piece, maintaining 20 a substantially constant pressure against the barrel lug stud at all times.

Should the spring 35 be broken, or for any other reason fail to thrust the take-down piece 31 forward in the manner described, the gun can 25 nevertheless be securely and operatively assembled. In this condition, as the magazine plug advances the spring pilot 32 will be pushed backwardly until it engages a spring pilot 34. The pilots are of such length that when this occurs 30 the cylindrical projection 242 on the barrel lug stud 241 is securely engaged within the cylindrical aperture provided therefor in the take-down piece 31, and thus the parts are securely held in their proper relative positions. 35

It is to be understood that the invention is susceptible of embodiment in many other forms than the illustrative one herein described, all of which fall within the scope of the appended claims. 40

What is claimed is:

1. In a take-down firearm comprising a barrel assembly and a stock assembly comprising a rigidly secured magazine tube, joining means whereby relative rotation of said assemblies permits their separation, securing means for preventing such relative rotation, means constantly urging said securing means toward effective position, and means for retracting said securing means against the force of said urging means comprising a member mounted for rotation relative to said securing means.

2. In a firearm comprising a barrel and a magazine tube located in substantial alignment with said barrel; means for securing said magazine tube to said barrel comprising a slidible member associated with said magazine tube, a take-down piece controlled by said slidible member, means associated with said barrel adapted to be engaged by said take-down piece, and means constantly urging said take-down piece into engagement with said barrel means.

3. In a firearm comprising a barrel and a magazine tube adapted to be held in parallel spaced relation; means for securing said magazine tube to said barrel comprising a take-down piece associated with said magazine tube, means associated with said barrel adapted for engagement by said take-down piece, means constantly urging said take-down piece into engagement with said barrel 65 means, and means comprising a manipulative device rotatably held on said magazine tube for retracting said take-down piece from engagement with said barrel means.

4. In a firearm comprising a barrel and a mag-

azine tube adapted to be held in parallel spaced relation to said barrel; means for securing said barrel to said magazine tube comprising a magazine plug arranged for longitudinal movement 5 with respect to said magazine, a take-down piece arranged for longitudinal movement with respect to said magazine plug, means constantly urging said take-down piece forward with respect to said magazine plug, co-operating means on said 10 take-down piece and said magazine plug whereby said take-down piece is retracted upon a retracting movement of said magazine plug, means mounted and rotatable upon said magazine for retracting and advancing said magazine plug, 15 and means associated with said barrel adapted for engagement by said take-down piece.

5. In a firearm, a magazine assembly, a receiver and a barrel adapted to be secured to said receiver by rotation relative thereto, co-operating 20 means on said barrel and magazine assembly preventing rotation of said barrel until correctly positioned with respect to said receiver, co-operating means on said barrel and magazine assembly for limiting the rotation of said barrel relative 25 to said receiver, and devices comprising a spring-pressed plunger for securing the barrel in the position in which it is stopped by said second means.

6. In a firearm, a magazine assembly, a receiver and a barrel adapted to be inserted in said receiver and thereafter rotated to secure it in said receiver, co-operating means on said barrel and magazine assembly for preventing rotation of said barrel until fully inserted in said receiver, 35 co-operating means on said barrel and magazine assembly for limiting the rotation of said barrel relative to said receiver, and devices comprising a spring-pressed plunger for securing the barrel in the position in which it is stopped by said 40 second means.

7. In a firearm, a magazine assembly, a receiver and a barrel adapted to be secured to said receiver by rotation relative thereto, co-operating means on said barrel and magazine assembly 45 preventing rotation of said barrel until correctly positioned with respect to said receiver, co-operating means on said barrel and magazine assembly for limiting the rotation of said barrel relative to said receiver, devices for securing said 50 magazine assembly to said barrel comprising a slidably member associated with said magazine assembly, a take-down piece associated with said barrel adapted to be engaged by said take-down piece,

and means constantly urging said take-down piece into engagement with said barrel means.

8. In a firearm, a magazine assembly, a receiver and a barrel adapted to be secured to said receiver by rotation relative thereto, co-operating 5 means on said barrel and magazine assembly preventing rotation of said barrel until correctly positioned with respect to said receiver, co-operating means on said barrel and magazine assembly for limiting the rotation of said barrel relative 10 to said receiver, devices for securing said magazine assembly to said barrel comprising a take-down piece associated with said magazine assembly, means associated with said barrel adapted for engagement by said take-down piece, 15 means constantly urging said take-down piece into engagement with said barrel means, and means associated with said magazine assembly for retracting said take-down piece from engagement 20 with said barrel means.

9. In a firearm comprising a barrel and a magazine tube, means for removably securing said magazine tube to said barrel comprising a take-down piece associated with said magazine tube, means on said barrel co-operating with said take-down piece, and means for retracting said take-down piece from said barrel means comprising a member rotatably mounted on said magazine tube and having a threaded engagement with said take-down piece for effecting translation 30 thereof.

10. In a firearm comprising a barrel and a magazine tube, means for removably securing said magazine tube to said barrel comprising a take-down piece slidably and non-rotatably supported 35 in said magazine tube, means on said barrel co-operating with said take-down piece, means for retracting said take-down piece from said barrel means comprising a member mounted for rotation but not translation on said magazine tube, 40 and connections whereby rotation of said member effects translation of said take-down piece relative to said magazine tube.

11. In a firearm comprising a barrel and a magazine tube, means for removably securing said 45 magazine tube to said barrel comprising a plug slidably held in said magazine tube, a finger piece rotatably held on said magazine tube and having a threaded engagement with said plug, a take-down piece slidably held in said plug, and means 50 associated with said barrel co-operating with said take-down piece.

CRAWFORD C. LOOMIS.
